HOLDER FOR A CIGARETTE LIGHTER

George L. Schick, Trumbull, Conn., assignor, by mesne assignments, to Scovill Manufacturing Company, Waterbury, Conn., a corporation of Connecticut

Filed Mar. 3, 1966, Ser. No. 1,278

Term of patent 14 years

(Cl. D48—27)

FIG. 1 is a perspective view of a holder for a cigarette lighter showing my new design;

FIG. 2 is a side view of the same;

FIG. 3 is a rear end view of the same;

FIG. 4 is a front view of the same; and

FIG. 5 is a top plan view of the same.

The lighter is shown in broken lines in FIG. 2 for illustration purposes only.

I claim:

The ornamental design for a holder for a cigarette lighter, substantially as shown and described.
